US00D478078S

(12) United States Design Patent (10) Patent No.: **US D478,078 S**
Miao et al. (45) Date of Patent: ** Aug. 5, 2003

(54) **STORAGE DEVICE**

D406,116 S * 2/1999 Huber et al. D14/351
D417,864 S * 12/1999 Holtzman et al. D14/351

(75) Inventors: **Chang-Ta Miao**, Taipei (TW);
Gwo-Chyuan Chen, Taipei (TW)

* cited by examiner

(73) Assignee: **Quanta Computer, Inc.**, Tao Yuan
Shien (TW)

Primary Examiner—Freda Nunn

(**) Term: **14 Years**

CLAIM

(21) Appl. No.: **29/165,255**

The ornamental design for a storage device, as shown and described.

(22) Filed: **Aug. 6, 2002**

DESCRIPTION

(51) LOC (7) Cl. **14-02**
(52) U.S. Cl. **D14/349**
(58) Field of Search D14/349-354,
D14/356; D13/162, 184, 199; 312/223.1-223.3;
360/99.01, 99.12; 361/690-696

(56) References Cited

FIG. 1 is a front, side perspective view of a storage device showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof.
